UNITED STATES PATENT OFFICE.

CALVIN M. REED, OF SUMNEYTOWN, PENNSYLVANIA.

RAIL-FASTENER.

SPECIFICATION forming part of Letters Patent No. 707,257, dated August 19, 1902.

Application filed December 27, 1901. Serial No. 87,476. (No model.)

To all whom it may concern:

Be it known that I, CALVIN M. REED, a citizen of the United States, residing at Sumneytown, in the county of Montgomery and State 5 of Pennsylvania, have invented new and useful Improvements in Rail-Fasteners, of which the following is a specification.

This invention relates to metallic railway-ties, and has for its object to provide an improved tie formed of sheet metal which will possess great strength, rigidity, and durability, which may be firmly anchored in the ballast of road-bed, so as to effectually resist any 10 tendency to creep or shift its position owing to the vibration and jar sustained from passing trains, to provide such a tie with novel, simple, and efficient means for firmly and securely attaching the rails thereto without the use of spikes or similar fastenings, and finally 15 to provide an improved tie of the character described formed entirely of sheet metal and capable of sustaining the weight of the heaviest freight and passenger trains, and which shall be both simple and durable in construction and capable of being manufactured at 20 relatively small cost.

To these ends my invention consists in the features and in the construction, combination, and arrangement of parts hereinafter 25 described, and particularly pointed out in the claims following the description, reference being had to the accompanying drawings, forming a part of this specification, wherein—

Figure 1 is a perspective view of one of my 30 improved ties and showing one of the rails attached thereto. Fig. 2 is a transverse sectional view thereof. Fig. 3 is a longitudinal sectional view of the same. Fig. 4 is a detailed longitudinal sectional view showing the parts 35 in the position they occupy before the rail is secured in place, and Fig. 5 is a perspective view of the under member of the tie viewed from the under side.

My improved tie broadly comprises two 40 arched beams constructed of sheet metal and superposed one upon the other, said beams being provided with oppositely-disposed tongues that are adapted to grasp the opposite sides or edges of the flanges of the rails and firmly 45 and securely hold the latter to their seats on the ties.

In Fig. 1 of the drawings is illustrated one

of my improved ties, which, as shown, consists of two arched beams, respectively indicated by the numerals 1 and 2. Each of 55 said beams is formed of heavy sheet metal and comprises a body portion consisting of a flat bar or plate 3, having its opposite sides or edge portions bent downwardly at an inclination to the body portion to form dependent flanges 4. The under or innermost beam 2 is made slightly smaller in cross-section than the beam 1, whereby the said beam 2 may be snugly fitted within the beam 1. Each of the beams is provided on its upper side or 60 body portion 3 and near its opposite ends with rectangular slots 5, said slots being formed by slitting the body portion of the beam longitudinally and then uniting the ends of said longitudinal slits by a transverse slit, and the 65 metal contained between said slits is then bent up to form overhanging tongues 6, as most clearly shown in Fig. 1 of the drawings. As shown, the tongues 6 of the upper beam 1 project in the same direction or, as shown in the 70 drawings, project toward the right, while both tongues 6^a of the lower beam also project in the same direction, but in opposite directions to the tongues 6. The tongues 6^a are made 75 slightly less in length than the width of the 80 slots 5 in the upper beam 1, whereby said tongues when the two beams are fitted together project through the slits 5, formed in the upper beam. Each of the beams is provided near one end in its upper body portion 85 3 with a bolt-hole 7, said bolt-holes when the two beams are fitted together in position to grasp the rail registering with one another for the reception of a bolt 8.

The end beam 2 is provided with anchor- 90 plates 10, each formed by making a vertical slit in one of the dependent flanges 4 of said beam and then bending a portion of said flanges lying on one side of said slit inward to form a triangular flange or lip 10, as most 95 clearly shown in Fig. 2 of the drawings.

In building the track the two beams are fitted one within the other with their tongues separated, as shown in Fig. 4, and the ballast is then tamped about and under the tie. The 100 rails are then laid on the upper side of the tie, one rail being disposed between each pair of the tongues. The upper beam is then moved lengthwise upon the lower beam and

forced tightly up into place until the tongues 6 and 6^a firmly and tightly fit over and grasp the opposite edges of the flanges 11 of the rails. When the beams are in this position, 5 the bolt-holes 7, as above described, register with each other. The bolt 8 is then passed through said bolt-holes, and the nut 9 is tightly screwed over the threaded end thereof, thus locking the beams against endwise movement 10 relatively one to the other. The rails are thus quickly, rigidly, and securely attached to the tie and without the use of spikes or similar fastenings. The anchor-plates 10 are firmly embedded in the ballast and prevent 15 any endwise movement of the ties in the road-bed, and hence the ties are not affected by the severe vibrations and jars incident to the passage of trains. By fitting one of the beams within the other, or, in other words, by super- 20 posing one upon the other, great strength and rigidity are imparted to the ties, whereby they are capable of sustaining the weight of the heaviest freight and passenger trains, and by providing said beams with depending and op- 25 positely inclined or flaring flanges 4 the ties are prevented from any lateral movement in the road-bed and are also sustained against sinking in the road-bed.

Having described my invention, what I 30 claim is—

1. A railway-tie comprising two arched metallic beams superposed the one upon the other, means carried by said beams for grasping the opposite edges of the flanges of the 35 rails, and means for locking said beams against endwise movement relatively one to the other, substantially as described.

2. A railway-tie comprising two arched metallic beams superposed one upon the other, 40 each provided on their opposite edges with depending and flaring flanges, tongues struck up from the upper sides of said beams and arranged to grasp the opposite edges of the flanges of the rails, and means for preventing 45 the endwise movement of said beams relatively to one another, substantially as described.

3. A metallic railway-tie comprising two sheet-metal beams superposed one upon the 50 other, each consisting of a flat body portion provided on its opposite edges with depending and flaring flanges, each of said beams being provided on its upper side with upwardly and horizontally projecting tongues, the 55 tongues of each beam extending in the same direction, and the tongues of one beam extending in an opposite direction to the tongues of the other beam to grasp the opposite sides of the flanges of the rails, and means 60 for locking said beams against endwise movement relatively one to the other substantially as described.

4. A railway-tie comprising two sheet-metal beams superposed the one upon the other, each

consisting of a flat body portion provided on 65 its opposite sides with depending and outwardly-flaring flanges, each of said beams being provided near its opposite ends with rectangular slits, the metal between said slits being struck up to form upwardly and horizontally projecting tongues, the tongues of one beam extending in a direction opposite to the tongues of the other beam to grasp between them the opposite edges of the flanges of the rails, and the tongues of the lower 75 beam projecting through the slots of the upper beam, and means for locking said beams against endwise movement relatively one to the other substantially as described.

5. A railway-tie comprising two sheet-metal 80 beams superposed the one upon the other, and each consisting of a flat body portion provided on its opposite sides with depending flanges, said beams being provided with upwardly and horizontally projecting tongues 85 arranged to grasp between them the opposite edges of the flange of the rails, the depending flanges of the under beams being provided with inwardly-projecting anchor-plates to prevent longitudinal movement of the tie 90 in the road-bed substantially as described.

6. A railway-tie comprising two sheet-metal beams superposed the one upon the other, each consisting of a flat body portion provided on its opposite edges with depending flanges, 95 tongues carried by said beams for grasping between them the opposite edges of the flanges of the rails, means for locking said beams against endwise movement relatively one to the other, the flanges of the under beam being vertically slotted, and the metal on one side of such slit being bent inward to form an anchor-plate to hold the tie against endwise movement in the road-bed substantially as described.

7. A railway-tie comprising two arched sheet-metal beams slidably superposed the one upon the other, said beams being provided with upwardly and horizontally projecting tongues, the tongues of one beam being disposed in the opposite direction to the tongues of the other beam to grasp the opposite edges of the flanges of the rail between them, each of said beams being provided at one end with a bolt-hole, said bolt-holes being arranged to register when the beams are in position to hold the rails thereto, and a bolt passing through said bolt-holes, and operating to hold said beams against endwise movement relatively one to the other, substantially as described.

In testimony whereof I have hereunto set my hand in presence of two subscribing witnesses.
